UNITED STATES PATENT OFFICE.

WILLIAM B. FRANKENSTEIN, OF ROCHESTER, NEW YORK, ASSIGNOR TO PRITCHARD STAMPING COMPANY, OF ROCHESTER, NEW YORK, A CORPORATION OF NEW YORK.

BAYONET-JOINT.

1,195,196.

Specification of Letters Patent. Patented Aug. 22, 1916.

Application filed October 8, 1915. Serial No. 54,899.

To all whom it may concern:

Be it known that I, WILLIAM B. FRANKENSTEIN, a citizen of the United States, and resident of Rochester, in the county of Monroe and State of New York, have invented 5 certain new and useful Improvements in Bayonet-Joints, of which the following is a specification.

This invention relates to a bayonet-joint 10 such as is used for securing together two cylindrical sheet-metal members, the invention being particularly designed for use in connection with lanterns, though applicable to other purposes.

15 The object of the invention is to produce a bayonet-joint of simple and inexpensive construction, which shall be convenient and reliable in use. To this end I employ, in connection with an outer joint-member 20 which is in the form of a sheet-metal cup or ring, a wire which constitutes both a reinforcement for the upper edge of this outer member, and also means for coöperating with the other joint-member in the novel 25 manner hereinafter described.

In the accompanying drawings: Figure 1 is a side-elevation of a portion of a lantern embodying the present invention; Fig. 2 is a 30 perspective view of a part of the lantern embodying the outer member of the bayonet-joint; and Fig. 3 is a section on the line 3—3 in Fig. 1.

The invention is illustrated as embodied 35 in a joint which secures the base or cup of a lantern to the body-ring or hoop. This body-ring 5 has a lower portion of reduced diameter, as shown particularly in Fig. 3, which constitutes the inner joint-member, while the outer joint-member 6 is embodied 40 in the upper part of the base or cup which supports the oil-font of the lantern. The inner member 5 is provided with radial projections in the form of two pins 7 diametrically arranged, and in order to receive these pins the upper margin of the outer member 45 6 is cut away, at two opposite points, to form recesses 8. The upper edge of the outer member is reinforced by means of a

wire, which is rolled into the edge in the usual manner. Above the recesses 8 the wire 50 has portions 9 which coöperate with the pins 7, when the two joint-members are locked together, as shown in Fig. 1. In order to permit the members to be brought to this position the wire is outwardly bent 55 or offset at two points 10, as shown in Fig. 2, and after the outer member has been raised against the shoulder on the inner member, the pins at this time entering through the recessed portions 10 of the wire, 60 the outer member is given a partial rotation in a right-hand direction, so as to bring the parts 9 of the wire above the pins, thus locking the two joint-members together.

In order to prevent accidental disengagement of the bayonet-joint members in a lantern it is customary to provide a spring-catch of some form. In accordance with the present invention this catch is formed cheaply and conveniently of one end of the 70 above-described wire. For this purpose the wire is bent, near its end, first downwardly and then horizontally, as shown in Fig. 2, and is provided with curved downwardly and upwardly extending offsets 12 and 13, 75 respectively. The space between the offset 13 and the part 9 of the wire is less than the thickness of the pins 7, but, owing to the resiliency of the wire, either of the pins may be caused to enter between these parts 80 and to be engaged by, and seated in, the offset 12, as shown in Fig. 1. The reverse rotation of the parts is then resisted by the engagement of the offset 13 with the pin, although the user may readily disengage the 85 parts by forcibly rotating them, owing to the resiliency of the wire.

I claim:

1. In a bayonet-joint, the combination of an inner member provided with radial projections; an outer member, of sheet-metal, having elongated recesses at its upper margin to receive said projections; and a wire rolled in the upper edge of the outer member extending over the recesses therein so as 95 to coöperate with said projections, and out-

wardly bent to permit the wire to be positioned above said projections.

2. In a bayonet-joint, the combination of an inner member provided with radial projections; an outer member, of sheet-metal, recessed at its upper margin to receive said projections; and a wire rolled in the upper

edge of the outer member and crossing the recesses therein so as to coöperate with said projections, one end of the wire being 10 formed into a spring-catch to coöperate with one of the projections and prevent accidental rotation of the joint-members.

WILLIAM B. FRANKENSTEIN.
